UNITED STATES PATENT OFFICE.

WALTER J. KENNEDY AND GEORGE YELLE, OF INDIAN ORCHARD, MASSACHUSETTS.

MONUMENT.

1,214,319.

Specification of Letters Patent. Patented Jan. 30, 1917.

Application filed October 2, 1915. Serial No. 53,806.

To all whom it may concern:

Be it known that we, WALTER J. KENNEDY and GEORGE YELLE, citizens of the United States, residing at Indian Orchard, 5 in the county of Hampden and State of Massachusetts, have invented certain new and useful Improvements in Monuments; and we do hereby declare the following to be a full, clear, and exact description of the 10 invention, such as will enable others skilled in the art to which it appertains to make and use the same.

This invention relates to new and useful improvements in monuments and is particularly adapted for exhibiting pictures and the like of a person.

Another object of this invention is to provide a monument which is hollow and carries a rotatable carrier for cards bearing inscriptions and the like.

Still another object of the invention is to provide a monument which may be easily and cheaply constructed and is preferably of hollow metal so as to lighten the construction of such devices.

With these and other objects in view, the invention consists in the novel combination and arrangement of parts which will be fully set forth in the following specification 30 and accompanying drawings, in which:

Figure 1 is a side view in elevation of a monument constructed in accordance with this invention. Fig. 2 is a vertical sectional view on the line 2—2 of Fig. 1. Fig. 3 is a 35 horizontal sectional view on line 3—3 of Fig. 2. Fig. 4 is a horizontal sectional view on line 4—4 of Fig. 2. Fig. 5 is a horizontal sectional view on line 5—5 of Fig. 2, and Fig. 6 is a diagrammatic perspective view of 40 the rotatable carrier for the cards and pictures to be exhibited.

Referring to the drawings, the numeral 1 designates the base of the device comprising the side walls 2 provided with the horizontal 45 walls 3 and this base is preferably arranged to form a series of steps as illustrated in the drawings. The shaft designated by the numeral 4 comprises the side walls 5, the rear wall 6 and the front wall 7, which front wall 50 is formed with the sight opening 8 which is surrounded by a suitable angle bracket 9 for supporting the doors of the device. A suitable cap 10 is secured to the upper end of the shaft 4 and is provided with the central 55 opening 11 through which the stem or standard 13 of the cross 14 extends. Secured to

the outer faces of the walls 5, 6 and 7 of the shaft 4 near its lower end are the troughs 15 for holding flowers, plants and the like and the chambers or receptacles 16 are secured to 60 the outer faces of these walls immediately above the troughs 15 for a like purpose.

A suitable spider designated by the character 17 is provided and supports the central socket 18, which is provided with an 65 aperture in which the pin 19 is slidable, the outer end of which extends through the rear wall of the shaft 4 and is provided with a knob 20. A suitable coil spring 21 surrounds the pin 19 and normally urges the 70 same inwardly so that its inner end extends into a notch 22 formed in the lower end of the standard 13.

Hingedly secured to the front wall 7 of the shaft 4 as at 23 is the outer door 24 75 which closes the sight opening and hinged to the upper bracket 9 surrounding this sight opening on the interior is the glass door designated generally by the numeral 25 comprising the channeled frame in which 80 the edges of the glass panel 27 are secured. It will thus be seen that the interior of the device will be protected against the elements by both the glass door and the outer door 24.

The exhibitor for the device consists of 85 the drive shaft 28 on which the hubs 29 are slidably mounted. The ends of this shaft are journaled in the side walls of the shaft 4 and one of said ends extends beyond the side wall and has secured thereto a crank 90 30 by means of which the exhibitor is rotated. Extending radially from the hubs 29 are the arms 31, the extreme outer ends of which terminate in suitable loops 32 through which the rods 33 are slidable and 95 the inner ends of these rods are formed with the loop 34 as clearly shown in Fig. 6. The outer ends of the rod 33 carry suitable rings 35 to which the ends of the coöperating bars are secured. Extending between the 100 radial arms on one of the hubs are the rods 36, the adjacent ends of which are provided with loops similar to the loops 32 and 34 so as to render the distance between the arms adjustable and connecting the arms which are in parallel relation and extending between the hubs are the bars or rods 38 provided with the loop 39 so that the hubs may be slid longitudinally on the shaft 28 and the length of the distance between said hubs 105 55 increased or decreased to fit cards of varying sizes.

It will be apparent from the foregoing that in use the device is set up in the manner illustrated in Fig. 2 and a suitable concrete filler 40 placed in the lower section of the base 1 to insure the proper positioning of the device and it remaining in place. The persons visiting the monument may open the outer door 24 and upon turning the crank 30 cause the exhibitor to revolve, thereby bringing pictures and various notes regarding the deceased in sight, thereby renewing and refreshing the memory. Due to the adjustability of the exhibitor, it will readily be seen that the sizes of the cards, pictures and the like may vary as the exhibitor may be made to fit different sized cards and it is also apparent that upon opening the door 27, various notes and adjustments of the interior mechanism may be made.

While in the foregoing there has been shown and described the preferred embodiment of this invention, it is to be understood that such changes may be made in the combination and arrangement of parts as will fall within the spirit and scope of the appended claims.

What is claimed is:—

1. A monument comprising a base formed with a plurality of strips of metal secured at their edges by angle bars, a hollow shaft

extending upwardly from the base consisting of sheets of metal secured at their edges by angle bars, the front wall of the hollow shaft provided with a transparent window, a transversely extending shaft rotatable immediately in the rear of the window, slideable hubs on said rotary shaft, adjustable arms on the hubs, and bars adjustably connected at the ends of the arms and adapted to be adjustable with relation to each other to fit cards of different sizes and a cap at the upper end of the shaft.

2. A monument comprising a base, a hollow shaft extending upwardly from the base, the front wall of said shaft being provided with a transparent window, a transversely extending shaft rotatable immediately in the rear of the window, slideable hubs on said rotary shaft, adjustable arms on the hubs and bars connected at the ends of the arms and adapted to be adjusted with relation to each other to fit cards of varying sizes.

In testimony whereof we affix our signatures in presence of two witnesses.

WALTER J. KENNEDY.
GEORGE YELLE.
